UNITED STATES PATENT OFFICE.

FRANK E. TEN EYCK, OF AUBURN, NEW YORK, ASSIGNOR TO AIR DEVICE MANUFACTURING COMPANY, OF CHICAGO, ILLINOIS, A CORPORATION OF MAINE.

COMBINED PUMP AND STARTER FOR EXPLOSIVE-ENGINES.

1,184,269.

Specification of Letters Patent.

Patented May 23, 1916.

Application filed June 25, 1914. Serial No. 847,191.

To all whom it may concern:

Be it known that I, FRANK E. TEN EYCK, a citizen of the United States, residing at Auburn, in the county of Cayuga and State 5 of New York, have invented certain new and useful Improvements in Combined Pumps and Starters for Explosive-Engines; and I do hereby declare the following to be a full, clear, and exact description of the 10 invention, such as will enable others skilled in the art to which it appertains to make and use the same.

My invention consists in the novel features hereinafter described reference being 15 had to the accompanying drawings which illustrate one embodiment of my invention selected by me for purposes of illustration, and the said invention is fully disclosed in the following description and claims.

20 Referring to the said drawings, Figure 1 represents a top plan view of my improved pump and starter operatively connected with an explosion engine and arranged upon a chassis of an automobile. Fig. 2 is an end 25 elevation of my improved pump and starter detached and drawn to a slightly larger scale, portions being broken away. Fig. 3 represents a plan view of the pump and starter, the cap or cover of the valve casing 30 being removed and parts of the figure being represented in section. Fig. 4 is a vertical sectional view of the pump and starter taken through two of the cylinders. Fig. 5 is a horizontal sectional view of the pump and 35 starter through the crank shaft casing. Fig. 6 is an enlarged detail sectional view of the valve casing and valve, with the cover of the valve casing removed. Fig. 7 is a bottom plan view of the valve detached. 40 Fig. 8 is a top plan view of the valve casing with the valve removed. Fig. 9 is a detail view showing a modified form of driving mechanism for the rotary valve, with provision for changing the relative position of 45 the valve with respect thereto.

The object of my invention is to construct a simple and powerful pump and starter for use preferably in connection with gasolene explosion engines installed in automobiles, 50 motor propelled boats, and other motor propelled vehicles which can be driven by the engine for the purpose of compressing air into a storage tank and which can also be operated as a motor, by the compressed air

from the storage tank for the purpose of 55 starting the engine and avoiding the necessity of manually cranking the same.

My invention comprises among other features an extremely simple construction of 60 pump and starter by means of which the multiplicity of valves heretofore necessary in connection with devices of this character is eliminated and great economy in the manufacture of the device is effected.

My improved pump and starter comprises 65 four cylinders 1, 2, 3, and 4, mounted upon a bed plate 5 having their axes parallel and arranged preferably at equal distance from each other, said cylinders being surmounted by a valve casing 6 containing a valve 7, the 70 said casing extending over a portion of each of said cylinders and communicating with each of said cylinders by a single port, the said ports being indicated at 11, 12, 13 and 14. In the preferred embodiment of my invention shown in the drawings, the four cylinders are cast integral with the bed plate 5 and the valve casing 6, the cylinders and valve casing being accurately bored and the valve casing being provided with a cap 75 or cover 8 which is in this instance screwed into the valve casing 6, the upper portion of which is provided interiorly with screw threads to engage exterior screw threads on the cap, suitable packing being provided if 80 necessary to make a tight joint. The cylinders are supported upon a crank case 9 which preferably comprises a body or casing provided with detachable end plates 10 bolted or otherwise secured thereto and 85 carrying bearings for a pair of crank shafts 15 and 16, each of which is provided with two cranks, the said cranks being indicated at 21, 22, 23, and 24, the cranks of each crank shaft being set at an angle of ninety 90 degrees to each other and the crank shafts being connected by means of intermeshing gear wheels 17 and 18 secured thereto, in this instance with the crank case 9, in such 95 manner that during every revolution the cranks of one shaft move upwardly, while the corresponding cranks of the other shaft move downwardly, thereby substantially equalizing the strain on the several crank shafts. The relations of the cranks are illustrated in Figs. 4 and 5, and in Fig. 4, for 100 example, in which arrows indicate the direction of rotation of the crank shafts, it will 105

be seen that the crank 21 is moving upwardly while the crank 23 is moving downwardly and that as soon as the cranks 22 and 24 pass off of the dead center the crank 22 will move upwardly, while the crank 24 will move downwardly. It will also be seen that when two of the cranks are on dead center on opposite sides of the axes of their respective shafts, the other two cranks will be ninety degrees from dead center, one moving upwardly and the other moving downwardly so that there is no tendency for the apparatus to stop on dead center at any time.

15 Each of the cylinders is provided with a piston movable therein and operatively connected by a connecting rod with one of the cranks the pistons being indicated by the numeral 19 and the connecting rods at 20, 20 and these may be of usual or any preferred construction. In the drawings I have shown the crank shafts 15 and 16 as formed in two parts and connected together by sleeves 15^a, 16^a, to which they are pinned, 25 but this is not essential, as the crank shafts may be formed each in one piece if preferred.

30 represents a vertically disposed shaft which extends from the crank case through 30 the bed plate 5 centrally between the four cylinders, and through the bottom of the valve casing 6 for driving the rotary valve. This shaft is preferably supported in a long sleeve or bushing 31, secured to the bed 35 plate 5 on its under side and projecting into the crank case, and the lower end of the shaft 30 is provided with a spiral gear 32 which meshes with a spiral gear 33 on one of the crank shafts, in this instance being 40 formed on the sleeve 16^a surrounding the central portion of the crank shaft 16, although this is not essential. By this means rotary motion is imparted to the valve actuating shaft 30 in time with the 45 gear crank shafts and the pistons connected therewith. The upper end of the shaft 30 is provided with means for attaching the rotary valve thereto and in this instance the shaft is provided with a pair of recesses 60 34—34 (see Fig. 8) which are engaged by pins or dowels 35—35 on the rotary valve. The shaft 30 preferably extends slightly above the bottom of the valve casing 6 (see Fig. 6) and the valve 7 is provided with a 65 central recess 36 in which the pins 35 are located, said recess being slightly deeper than the projecting pieces of the shaft 30 to enable the bottom of the valve 7, which is accurately ground, to rest at all times on 70 the bottom of the valve casing. The shaft 30 is also provided with a longitudinally disposed exhaust passage 37 connected at its upper end with a radial slot or recess 38 and at its lower end with a radial discharge 75 aperture 39 communicating with the atmos-

phere. The rotary disk valve 7 is provided with a curved slot 40 which extends through an arc of slightly more than ninety degrees, the said slot being so arranged as to uncover successively the ports 11, 12, 13, and 14, connected with the respective cylinders, and being so constructed as to uncover each port a little before the instant when the preceding port is closed by the solid portion of the valve. The valve 7 is also provided at its under face with a curved recess or channel 41 of substantially the same, or slightly greater, length than the slot 40 and having its central portion diametrically opposite the central portion of the slot 40, and the said recess 41 is connected by the radial channel 42 with the central recess 36 of the valve so that when the valve is placed in engagement with the valve shaft 30 as best seen in Fig. 6, the recess 42 will establish 80 communication through the slots 38 and exhaust passage 37 with the exhaust aperture 39, the pins 35, and recesses 34, before referred to, being so located as to hold the valve with the passage 42 in alignment with 85 the slot 38 in the shaft 30. The cap or cover 8 when in its closed position, as shown in Fig. 4, provides a slight space indicated at 8^a between it and the upper portion or slot 7^a of the valve 7, and said cap or cover 90 is provided with a central aperture which is connected by means of a pipe 50 with a storage tank 51, indicated in Fig. 1.

From the foregoing description, it will be apparent that if the crank shafts were 100 driven from a prime motor and the device is operating as a pump, air will be admitted through the aperture 39, the longitudinal passage 37, slot 38, passage 42, and recess 41, successively to the several ports 11, 12, 105 13, and 14, connected with the cylinders and as the cycle of the pump progresses, each cylinder will receive air in this manner during the downward stroke of its piston, and the air in each cylinder will be compressed 110 on the upward stroke of its piston, the compressed air being forced through the cylinder port and through the slot 40 in the rotary valve, into the valve casing from whence it passes by pipe 50 to the tank. If 115 it is desired to use the device as a motor acting under the pressure of the stored compressed air, the compressed air will be supplied from the storage tank through the pipe 50 to the valve casing, and will be distributed by the rotary valve successively to the four cylinders to actuate the pistons therein, the expanded air being exhausted 120 on the return stroke of the piston through the cylinder port, the curved recess 41 in 125 the valve, the radial passage 42, and the slot 38, passage 37, and aperture 39 in shaft 30, to the atmosphere.

In Fig. 1, which shows my improved pump and starter in operative relation with 130

an explosion engine or internal combustion engine, 60 represents the engine which may be of any usual or preferred construction, and I have shown my improved pump and 5 starter arranged alongside of the engine and operatively connected therewith in such a manner that the engine may operate the device when it is used as a pump and when it is used as a starter it may be connected 10 with the engine for starting the same. In the form of the invention herein shown, I have provided suitable clutch mechanism and gearing interposed between the engine and the combined pump and starter to accomplish the desired result, it being understood that the engine shaft will always turn in the same direction while the crank shafts of the combined pump and starter, as heretofore described, will be rotated in one direction 15 when acting as a pump and in the other direction when the device is acting as a motor, which necessitates the reversal of the gearing between the engine shaft and the pump and starter. This may be accomplished in different ways but a convenient form of mechanism for this purpose is shown in Fig. 1, in which the crank shafts 15 and 16 are provided with pinions 52 and 53, loosely mounted on their respective 20 shafts and each engaging an intermediate idle pinion 54 mounted on a stud 55, extending from an adjacent end plate of the crank case. One of the crank shafts, in this instance the crank 16, is provided with a 25 sprocket wheel 56 loosely mounted on the shaft, but which is rigidly secured to the adjacent gear wheel 53. In this instance the gear wheel is provided with a sleeve upon which the sprocket wheel 56 is mounted and keyed, as shown in Fig. 5. The 30 sprocket wheel 56 is connected by means of a sprocket chain 57 with a sprocket 58 on the crank shaft of the engine or other shaft operatively connected with the crank shaft. 35 The loose gear wheels 52—53 are provided with clutch members 52^a—53^a, and each crank shaft is provided with a movable clutch member 52^b—53^b splined to the shaft or otherwise secured, so as to permit longitudinal 40 movement thereof. By throwing in one of these clutches, the combined pump and starter can be actuated from the engine in one direction as a pump, and when the device is operated reversely as a starter, the other clutch will be thrown in and the first clutch thrown out so that rotation in the proper direction will be imparted to the engine crank shaft.

In the use of my improved pump and 45 starter, on automobiles and other motor vehicles, I prefer to provide means within convenient reach of the operator, and preferably near the steering wheel by means of which the vehicle is steered, for actuating 50 these clutches and in the present instance I

have shown the movable clutch members provided with annular grooves to receive yokes 61 and 62, which are carried by a horizontally disposed rock bar 63, pivotally connected with the end plate of the crank 70 case 9. One end of this rock bar is connected by a link 64 with an arm 65 pivotally mounted on the other end of the crank case at 66 and provided with a rack segment 67, which is engaged by a pinion 68 on a rock 75 shaft 69, preferably mounted in bearings secured to the steering head 70 and extending to a point adjacent to the steering wheel, the shaft 71 of which is indicated in Fig. 1, the wheel being broken away. In order to steady 80 the other end of the rock bar 63, I prefer to provide it with a plunger 63^a, engaging a stationary guide 64^a, which may be conveniently formed on or secured to the crank case 9. The rock shaft 70 is provided 85 with an operating handle 72 and adjacent thereto I prefer to provide an indicating plate 73 having suitable indications thereon to show the neutral position of the lever in which, as shown in Fig. 1, both 90 clutches are out of operative condition, and also indicating the opposite positions of the lever for throwing one of said clutches in when the device is used as a pump and for throwing the other clutch in when the device 95 is used as a starter. I also prefer to have this handle or lever 72 actuate the valve which controls the passage of air to and from the tank 51 through the pipe 50, and in this instance I have shown a control 100 valve 74 interposed between the pipe 50 and the tank 51 and provided with an actuating arm 75 connected by a link 76 with an arm 77 secured to the rock shaft 69, the said valve 74 having a closed central position 105 and two open positions on opposite sides of the central position so that when the lever 72 is moved to either position, the valve 74 will be opened to establish communication between the tank and the pump and starter. 110 I also prefer to provide the tank 51 with a shut off valve, or cock 51^a for cutting off the tank from the rest of the apparatus when the apparatus is not in use, to prevent leakage of stored air. In Fig. 1, 80 115 represents the dash of the automobile or other motor vehicle and I prefer to provide a pressure gage, indicated at 81, which may be conveniently supported in or upon the dash and is operatively connected with the 120 pipe 50 to indicate the pressure in the tank. The tank or the pipe 50 may also be provided with a safety valve which in this instance is indicated at 51^b to prevent overcharging of the tank, and which may be set 125 for the desired pressure, say for example, two hundred pounds.

From the foregoing description, it will be obvious that if the engine is running and the hand lever 72 is thrown to the "pump" posi- 130

tion, the appropriate gear wheel 52 or 53 (in this instance gear 52) will be connected with the engine crank shaft, and at the same time the air valve 74 will be opened so that the engine will operate the combined pump and starter as a pump compressing air and forcing it into the tank 51 until the desired pressure is obtained, when the hand lever 72 and valve 74 will be restored to neutral position. If the engine is at rest and it is desired to start the same, it is only necessary to throw the hand lever 72 in the opposite direction, thereby throwing in the clutch for gear wheel 53 and simultaneously opening the air valve 74 when the compressed air in the tank returning through the pipe 50 will actuate the pistons in the cylinders and turn over the engine until it begins to act under the explosions of its explosive mixture when the lever 72 will be restored to its neutral position.

In some instances I may dispense with the reversing gearing between the engine and the combined pump and starter by providing means whereby the position of the rotary disk valve may be shifted one hundred and eighty degrees with respect to its actuating shaft in which case the crank shafts of the combined pump and starter will be actuated in the same direction whether the device is operating as a pump or as a starter, as will be readily understood. In Fig. 9 I have shown one form of mechanism by which the shifting of the disk valve with respect to its shaft may be conveniently effected. In this figure 7^a represents the disk valve which is constructed and operates in all respects in the same manner as the valve 7 heretofore described, except in the following particulars. The valve actuating shaft is made in two parts 30^a and 30^b, the part 30^a being connected with the valve, and the part 30^b being connected with the spiral gear 32^a. Upon the meeting portions of the shaft sections 30^a and 30^b I provide a longitudinally movable sleeve 90 which is provided with a pair of spiral or inclined slots 91—92 which engage pins 93—94, one of which is secured to the shaft member 30^a, and the other of which is secured to the shaft member 30^b. The said slots extend in this instance quarter way around the sleeve 90 and the pins and slots are so arranged that on shifting the sleeve longitudinally they will act upon the pins 93—94, and as the lower end of the shaft is held in fixed position by the engagement of the spiral gear 32 with its driving spiral gear, the slot 91 will effect a quarter revolution of the valve 7^a with respect to the sleeve, while the slot 92 will effect another quarter revolution of the sleeve and valve with respect to the lower shaft member 30^b, thus rotating the valve 7^a one hundred eighty degrees with respect to the lower shaft member 30^b and effectually re-

versing the valve. The sleeve 90 is shown as provided with an annular grooved portion 95 which is engaged by projections from a yoke 96 actuated by a suitable lever 97 which may be operatively connected with the hand lever 72 or other actuating device by suitable link connections in any desired way. When this mechanism shown in Fig. 9 for reversing the position of the valve is employed the reversing mechanism between the engine and the pump and starter can be dispensed with and one of the crank shafts may be provided with a sprocket or other gear loosely mounted thereon and operatively connected with the engine crank shaft, a single clutch being provided for connecting the gear or sprocket on the pump crank shaft therewith when the device is used either as a pump or as a starter.

It will be seen that my improved pump and starter is extremely simple and can be cheaply made and readily assembled and maintained in proper working condition as there is only one valve controlling the four cylinders, the communicating ports of which act both as inlet and exhaust ports. The construction also provides a combined pump and starter of great power and efficiency, while the individual cylinders are of small size and the whole apparatus is extremely compact and convenient to be installed in connection with the internal combustion engine.

I have shown and described the four cylinders as being equally distant from each other, and this is my preferred construction. It is obvious, however, that they might be arranged in pairs above the respective crank shafts without being equally distant from each other, the cylinder ports in the valve casing being suitably connected with the cylinders. The equally distant arrangement of the cylinders, however, is more symmetrical and permits the uniform arrangement of the cylinder ports.

What I claim and desire to secure by Letters Patent is:—

1. In a device of the kind described, the combination with four cylinders having their axes parallel and disposed equidistantly about a common center, a piston working in each of said cylinders, a single valve casing for all of said cylinders having four ports arranged in a circle, said casing having an aperture adapted to be connected with a reservoir of compressed fluid, and a separate aperture connected to the atmosphere, of a rotary valve in said casing, provided with means for alternately connecting one of said ports with the casing aperture communicating with the pressure fluid reservoir, and simultaneously connecting another of said ports with the casing aperture communicating with the atmosphere, driving connections including cranks

operatively connected to said pistons, and operative connections between said driving connections and said valve.

2. In a device of the kind described, the combination with four cylinders having their axes parallel and disposed equidistantly about a common center, a piston working in each of said cylinders, a single valve casing supported by and secured to all of said cylinders, and provided with a circular valve seat concentric with the common center about which the cylinders are disposed, said valve seat being provided with four ports, one of which communicates with each of said cylinders, said valve casing being also provided with an aperture adapted to be connected to a reservoir of compressed fluid and being also provided with an aperture communicating with the atmosphere, 10 a rotary valve in said casing provided with means for bringing said ports consecutively into communication with said aperture communicating with the pressure fluid reservoir, and simultaneously bringing another 15 of said ports into communication with the atmosphere, a piston in each of said cylinders, driving connections including cranks operatively connected with said pistons, and operative connections between said driving 20 connections and said valve.

3. In a device of the kind described, the combination with four cylinders having their axes parallel and disposed equidistantly about a common center, a piston working in each of said cylinders, a valve casing formed integrally with said cylinders and uniting them at their outer ends and being disposed concentrically with the common center about which said cylinders are 30 arranged, said valve casing being provided with ports communicating with said cylinders and having an aperture communicating with the atmosphere, and an aperture adapted to be connected with a fluid pressure reservoir, a rotary valve in said valve casing, a piston in each of said cylinders, driving connections including cranks operatively connected with said cylinders and connections from the said driving connections to 40 said rotary valve.

4. In a device of the kind described, the combination with four cylinders having their axes parallel and disposed equidistantly about a common center, a piston working in each of said cylinders, said cylinders being open at their inner ends and connected integrally by a base plate, a valve casing formed integrally with said cylinders and connecting their outer ends, said casing being arranged concentrically with the common center around which the cylinders are disposed, the said valve casing being provided with ports communicating with said cylinders, an aperture communicating with the atmosphere, and an 50

aperture adapted to be connected to a fluid pressure reservoir, a rotary valve in said valve casing, a piston in each of said cylinders, driving connections including cranks connected with said pistons, operative connections between said driving connections and said valve. 70

5. In a device of the kind described, the combination with four cylinders having their axes parallel and disposed equidistantly about a common center, a piston working in each of said cylinders, a single valve casing for all of said cylinders, secured to and supported by said cylinders and arranged concentrically with the center 80 around which the cylinders are disposed, said valve casing being provided with ports communicating with said cylinders, an aperture adapted to be connected with a pressure fluid reservoir, and an aperture communicating with the atmosphere, a rotary valve in said valve casing, a pair of parallel crank shafts each provided with two cranks, gearing connecting said crank shafts, a piston in each of said cylinders, connections between said cylinders and said cranks, and operative connections between said crank shafts and said rotary valve. 85

6. In a device of the kind described, the combination with four cylinders, and a piston working in each of said cylinders, of a pair of parallel crank shafts each provided with two cranks disposed at substantially right angles to each other, gearing connecting said crank shafts and holding 90 them in such relation that the vertical movement of each crank will be in a direction opposed to the vertical movement of a crank of the other shaft, connections between each piston and one of said cranks, a valve casing provided with cylinder ports communicating with said cylinders, said valve casing being provided with a passage adapted to be connected with a tank and being also provided with a combined inlet and exhaust 100 passage, a rotary valve in said valve casing for controlling said ports and passage, and operative connections between one of said crank shafts and said valve. 105

7. In a device of the kind described, the combination with four cylinders, and a piston working in each of said cylinders, of a pair of parallel crank shafts, each provided with two cranks disposed substantially 115 at right angles to each other, intermeshing gears connecting said crank shafts for causing them to rotate in opposite directions and maintaining said cranks in such relation that vertical movement of each crank will be in a direction opposite to the direction of movement of a crank of the other crank shaft, a valve casing provided with cylinder ports communicating with said cylinders, said casing being also provided with a passage adapted to be connected to a tank, and 120

125

130

being also provided with a combined inlet and exhaust passage communicating with the atmosphere, a rotary valve in said valve casing for controlling said ports and passages, and operative connections between one of said cranks and said valve for rotating the valve.

8. In a device of the kind described, the combination with four cylinders having 10 their axes parallel, a piston in each cylinder, a pair of crank shafts having their axes parallel, connections between each of said crank shafts and two of said pistons, gearing connecting said crank shafts so as to cause them to rotate in opposite directions, 15 said shafts being rotated, when the device is used as a starter, in directions opposite to their directions of rotation when the device is used as a pump, and means for independently connecting each of said crank shafts with the shaft of a prime motor 20 whereby the said prime motor shaft may rotate in the same direction regardless of the direction of rotation of the crank shafts.

9. In a device of the kind described, the combination with four cylinders having their axes parallel, a piston in each cylinder, a pair of crank shafts having their axes parallel, connections between each of said crank shafts and two of said pistons, gearing connecting said crank shafts, said shafts being rotated, when the device is used as a 25 starter, in directions opposite to their directions of rotation when the device is used as a pump, and gearing for connecting said crank shafts with the shaft of a prime motor, said gearing being provided with means for maintaining the proper relative 30 rotation of the crank shafts regardless of which one of the said shafts is in working 35 engagement with the shaft of the prime motor.

10. In a device of the kind described, the combination with four cylinders having 45 their axes parallel, a piston in each cylinder, a pair of crank shafts having their axes parallel, gearing connecting said shafts for rotation in opposite directions, connections between each of said crank shafts and two 50 of said pistons, a gear loosely mounted on each of said crank shafts, means for connecting said gears so as to cause them to rotate in the same direction, means for connecting one of said gears to the shaft of a prime motor, and clutches for independently 55 connecting said gears to their respective shafts.

11. In a device of the kind described, the combination with four cylinders having 60 their axes parallel, a piston in each cylinder, a pair of crank shafts having their axes parallel, gearing connecting said shafts for rotation in opposite directions, connections between each of said crank shafts and two 65 of said pistons, a gear loosely mounted on

each of said crank shafts, means for connecting said gears so as to cause them to rotate in the same direction, means for connecting one of said gears to the shaft of a prime motor, a clutch mechanism on each 70 of said shafts for connecting it with the loose gear mounted thereon, and operating mechanism connected with both of said clutches for throwing one of said clutches into operative position and holding the 75 other clutch simultaneously out of operative position.

12. In a device of the kind described, the combination with four cylinders having 80 their axes parallel, a piston in each cylinder, a pair of crank shafts having their axes parallel, gearing connecting said shafts for rotation in opposite directions, connections between each of said crank shafts and two 85 of said pistons, a gear loosely mounted on each of said crank shafts, means for connecting said gears so as to cause them to rotate in the same direction, means for connecting one of said gears to the shaft of a prime motor, a clutch mechanism on each 90 of said shafts for connecting it with the loose gear mounted thereon, a pivoted lever connected with both of said clutches for throwing one or other of said clutches into 95 operative position, said clutches being normally in inoperative position, and actuating means for said lever.

13. In a device of the kind described, the combination with four cylinders having 100 their axes parallel, a piston in each cylinder, a pair of crank shafts having their axes parallel, gearing connecting said shafts for rotation in opposite directions, connections between each of said crank shafts and two 105 of said pistons, a gear loosely mounted on each of said crank shafts, means for connecting said gears so as to cause them to rotate in the same direction, means for connecting one of said gears to the shaft of a prime motor, a clutch mechanism on each of 110 said shafts for connecting it with the loose gear mounted thereon, a pivoted lever connected with both of said clutches for throwing one or other of said clutches into operative position, said clutches being normally 115 in inoperative position, and actuating means for said lever, a pressure reservoir operatively connected with said pistons, a distributor interposed in said connection, a controlling valve for the connection between 120 said clutch actuating lever.

14. A device of the kind described, the combination with four cylinders having 125 their axes parallel and disposed equidistantly about a common center, a piston working in each of said cylinders, a single valve casing for all of said cylinders having four ports arranged in a circle, said casing having an aperture adapted to be connected with a reservoir of compressed 130

fluid, and a separate aperture communicating with the atmosphere, of a rotary valve in said casing provided with means for alternately connecting one of said ports with the casing aperture communicating with the pressure reservoir, and simultaneously connecting another of said ports with the casing aperture communicating with the atmosphere, a pair of crank shafts having parallel axes, connections between each of said crank shafts and two of said pistons,

gearing connecting said crank shafts, driving gearing connecting said rotary valve with one of said crank shafts and means for reversing the position of said valve with respect to said driving gearing.

In testimony whereof I affix my signature in the presence of two witnesses.

FRANK E. TEN EYCK.
